UNITED STATES PATENT OFFICE.

JOSEF FISCHER, OF BADEN, SWITZERLAND, ASSIGNOR TO AKTIENGESELLSCHAFT BROWN BOVERI & CIE., OF BADEN, SWITZERLAND, A JOINT-STOCK COMPANY OF SWITZERLAND.

ELECTRICAL TRANSFORMER CONSTRUCTION.

Application filed February 27, 1926, Serial No. 91,009, and in Germany March 9, 1925.

This invention relates to construction of electrical transformers, and finds its particular utility in a construction of transformers of large size. It has to do primarily with the tapping arrangements of the transformer.

The general object of the invention is the provision of a construction which affords a desired variety of tappings in minimum space, and wherein possible injurious effects, incident to the use of the different tappings, are avoided.

One of the specific objects of the invention is a construction which will avoid the creation of circulating currents in connected secondary coils of the transformer, or minimize their heating effects.

Other objects will be pointed out or indicated hereinafter, or be obvious to one skilled in the art, upon an understanding of the present disclosure.

In the drawing forming a part of this specification I illustrate diagrammatically various arrangements in accordance with the invention, but it is intended that the appended claims cover all other and different arrangements falling within the true and most comprehensive scope of the invention in the art. In the drawing,

Fig. 1 is a diagram of a usual tapping arrangement employed in transformers having parallel connected secondary branches,

Fig. 2 is a diagram illustrating one arrangement contemplated by the invention, and

Figs. 3 to 6 inclusive are diagrams illustrating other arrangements in accordance with the invention.

Referring to these illustrative arrangements, let it be understood that in each instance *a* designates the primary of the transformer and *b* and *c* branches of the secondary winding, which are connected in parallel at their ends. According to a tapping arrangement quite generally employed, tappings such as *d*, *e* and *f* are connected with corresponding portions of the windings *b* and *c*, as by conductors *i* and *k*, thus forming inter-connections between the branches at the tapping points. As a result, an instant current flow, when the tapping *e* is in use, will be as indicated by the arrows in Fig. 1, the portions marked *o* being without

current if the inductive effects in the two branches *a* and *b* are exactly uniform. As mathematical uniformity is not usually attained in commercial manufacture, however, the working portions of the two branches will not have exactly the same voltage, and as a result circulating currents will be produced, having undesirable heating effects and affecting the efficiency of the transformer.

In an arrangement contemplated by my invention, the secondary branches *b* and *c* are not cross-connected at the taps, the respective tappings having connection only with respective branches, as illustrated by the arrangement of the tappings *e'* and *f'* in Fig. 2, both connected to the branch *b* only, or by the arrangement shown in Fig. 3, wherein the tappings *g* and *h* are both connected to branch *b* only and arranged alternately with tappings *e'* and *f'*. The arrows in Fig. 2 indicate the instant current flow with the tapping *e'* in use, and in Fig. 3 with the tapping *g* in use.

By such arrangements the creation of circulating currents between the parallel connected secondary branches is avoided, or their heating effects minimized, and a desired variety of tappings is afforded without necessitating interconnections of the branches, which are troublesome in manufacture and require a substantial amount of space. Furthermore, with this arrangement of tappings, more of them may be provided in a given space than with the previous arrangement, and thus a greater number of voltages rendered available.

The invention may be utilized in conjunction with an interconnected tapping, as illustrated in Fig. 4, when it may be desired to minimize the copper losses incident to use of the lower voltage tapping. In this diagram the tapping *f* is interconnected with the branches *b* and *c* through the connection *m*, and the single branch tappings *e'* and *p'* are arranged at the higher voltage side of the tapping *f*, the latter being sufficiently removed from the end connection *d* to interpose between them an amount of the windings sufficient to dissipate the heating effect of circulating currents resulting from the difference in voltage between the active portions of the branches.

If it is desired to provide more than two parallel connected branches with taps according to the invention, the part *n* of the tapped branch *p* (Fig. 5), which is heavily loaded by the sum of the currents of the branches *b* and *c*, may be given a larger copper cross-section. For tapping of a still larger number of branches, such as the four branches *b*, *c*, *p* and *q* shown in Fig. 6, the branches may be connected up into equal groups by the customary cross-connections, and the groups tapped separately. As shown in said figure, one group is comprised of the branches *b* and *p*, which are cross-connected by the connection *h* and have the tapping *f*², the other group comprising the branches *c* and *q* having the cross-connection *i'* and the tapping *e*².

What I claim is:

- 20 1. Transformer construction comprising secondary branch windings of the same phase connected in parallel at their ends, with tappings on respective branches, the tappings on one branch being insulated from the point of the potential on the other branch.
- 28 2. Transformer construction comprising secondary branch windings of the same phase connected in parallel at their ends and with tappings all on the same branch.
- 35 3. Transformer construction comprising secondary branch windings connected in parallel at their ends and having intermediate tappings, the tappings on one branch being insulated from the tappings on the other branch.
- 40 4. A transformer comprising a pair of parallel windings of the same phase connected at their ends, and intermediate tappings on one of said windings, said tappings being insulated from the points of corre-

sponding potential on the other of said windings.

5. A transformer comprising a pair of parallel windings of the same phase connected at their ends, a set of intermediate tappings on one of said windings, and a set of intermediate tappings on the other of said windings insulated from the tappings of the first set. 45

6. A transformer comprising a pair of parallel windings of the same phase connected at their ends, a set of intermediate tappings on one of said windings, and a set of intermediate tappings on the other 55 of said windings insulated from the tappings of the first set, the tappings of one set being of a different potential than the tappings of the other set.

7. A transformer comprising a pair of parallel windings of the same phase connected at their ends, a set of intermediate tappings on one of said windings insulated from the points of corresponding potential on the other of said windings, and an additional set of tappings connecting points of corresponding potential on both of said windings. 60

8. In a transformer, a plurality of branch windings of the same phase connected in parallel at their ends, and a plurality of intermediate tappings of different voltages on said windings, successive tappings being on different branches of said windings, the tappings of one potential on one of said 75 branches being insulated from a point of corresponding potential on another of said branches. 70

In testimony whereof I have hereunto subscribed my name at Zurich, Switzerland 80 on the 3rd day of February A. D. 1926.

JOSEF FISCHER.
